UNITED STATES PATENT OFFICE

2,238,172

HOT AIR FURNACE

Rudolf Jovanovitz, St. Bernard, Ohio

Application June 1, 1939, Serial No. 276,325

5 Claims. (Cl. 237—48)

My invention relates to heating furnaces and particularly to furnaces for domestic heating plants wherein there is a combined gravity flow and forced air circulation.

In the art it is old in domestic heating plants to have a return duct for cold air from the building, which duct is divided into a gravity flow conduit and a forced air conduit by which the air to be reheated and recirculated is combined and flows into the shell of the furnace around the fire pot where, after it is heated, the warm air rises through the various ducts to the heat outlets within the building.

As far as I am advised, such combinations of gravity return flow with forced air return flow have as a disadvantage a widely variable flow of air so that when the blower or fan forcing the draft is in operation, too much air is caused to flow and when the blower or fan is cut off, there is too little circulation of air.

It is an object of my invention to provide a system for combined gravity flow and forced air circulation in a heating plant wherein variations in the flow of heated air can be regulated within much more restricted variation of air circulation than has heretofore been possible.

It is specifically an object of my invention to combine a forced air circulation with a gravity flow circulation wherein the forced air is induced through an elongated jet which causes the forced air to exert a siphon effect which carries with it a desired flow of air which does not pass through the blower.

It is a further object of my invention to so distribute the flow of induced air that it will be injected into the casing surrounding the fire pot of the furnace in a continuous flow without eddy currents in which condition it exerts a substantially constant pull on the intake from the gravity air duct so as to provide a well regulated flow of air.

The above objects and other specific objects in design and arrangement of the mechanical parts employed which will be later described, I accomplish by that certain combination and arrangement of parts of which I have shown a preferred modification which represents the installation in my own home where I have observed the many advantages and improvements of the particular system described.

Referring to the drawing:

Figure 1 is a side elevation of a preferred system.

Figure 2 is a detail perspective view showing my preferred construction of elongated jet injector.

Figure 3 is a detail plan view of the jet illustrated in Figure 2 taken along the line 3—3 of Figure 1.

Figure 4 is a sectional view taken along the line 4—4 of Figure 1.

The furnace has an outer shell 1 which surrounds the fire pot 2 within which the fuel is burned to heat the fire pot. There is a chamber 3 between the fire pot and the outer shell of the furnace within which air currents are heated by the fire pot and rise through conduits such as are indicated at 4 from which they are discharged through warm air registers as indicated at 5 to heat the air within the building. The return flow of air from the building passes through a grille 6 to the casing 7. The casing is in the form of a metal box of enlarged cross sectional area as illustrated. From the base of the casing, a conduit 8 extends down vertically to a position 10 where it is connected to the jet mixer generally indicated at 9.

The casing 7 has a conduit 10 connected thereto which conduit has an end 11 which extends up to close proximity to the top of the casing 7 so that the warmer air currents returning through the grille 6 are drawn into the induced air system.

The conduit 10 is subdivided into two branch conduits 12, as indicated in Figure 4, and I have shown a blower 13 having inlets 14 for the air which comes from the right hand conduit 12 and inlet 15 for the air which comes from the left hand conduit 12.

The blower may be operated by means of a motor 16 and pulley drive 17.

The conduits 12 discharge into a hollow box-like casing 18 subdivided into two compartments by the wall 19.

The discharge from the blower passes through a conduit 20 preferably having a damper 21 therein, and is connected to the jet mixer 9.

While I have referred to the apparatus indicated at 9 as a jet mixer, I do not thereby wish to be restricted to the general class of jet mixers such as are known in this art. The term "jet mixer" is a convenient description for the assembly indicated by the combination of parts 9 whether or not the action of this mechanism is in accordance with the well known principle of jet propulsion.

The mixer 9 has a wide and shallow duct 22 through which the induced air is driven from the blower 13. A flange 23 is bolted to the furnace and extending beyond the plane of contact of the flange I have shown an upwardly extending lip

24 or plate which I find of considerable utility in connection with causing an even flow of air.

The upper portion of the apparatus 9 consists of a wide and shallow duct 25 through which gravity air flows or is drawn depending on the operation of the blower.

In the casing 18 I preferably install a spun glass filter 26 through which the air passing down through the conduits 12 is filtered before being drawn into the blower.

In ordinary operation when the requirements for heated air are low, the motor 16 and blower 13 are not in operation, and descending cool air from the building passes down through the duct 8 through the conduit 25 into the space 3 surrounding the fire pot where it is warmed and passes up through the conduits 4. When there are greater requirements for heated air, ordinarily controlled by means of a thermostat within the building, the electrical controls for the motor 16 are closed so that the motor is started up and air is then drawn down through the conduit 10 and the branch conduits 12 and ejected in a continuously moving current through the conduit 22. The eddy currents caused by the upwardly extending plate 24 cause a suction of air to be drawn in through the conduit 25 from the gravity return flow system and the amount of air forced into the space 3 is moderately increased.

I find that the quantity of air passing down through the gravity flow system is substantially increased over the quantity of air which flows down through the conduit 8 when the blower is not in operation.

I find that I provide a sort of jet injector effect 35 so that by a moderate flow of injected air, I substantially increase the flow of the combined injected and the gravity supply.

As typical dimensions of the conduit 22 at its discharge end into the furnace, I have found that 40 dimensions of 3 inches in height by substantially 30 inches in width provide a satisfactory operation.

I of course do not wish to be limited to the specific dimensions shown inasmuch as variations in size and dimensions will readily occur to those skilled in the art to accommodate my system for smaller or larger heating plants.

I have shown my system of combining gravity flow and forced air circulation in combination 50 with a heating furnace, but it should be understood that in the summertime when it is desired to employ the heating system as a cooling system, that refrigerating apparatus may be substituted for the fire pot 2 so that my invention in its broader aspects consists in providing suitable apparatus and a system of controlling the flow of gases to equipment which is to condition the air either by warming it or cooling it.

With air cooling apparatus, such as that to which I have referred, ordinarily the conduits through which cooled air passes to the building have forced air circulation between the delivery conduits and the chamber in which the air is cooled, which is created by a fan or blower. This is because cool air will not rise.

Having thus described my invention what I claim as new and desire to secure by Letters Patent is:

1. In a combined gravity flow and forced air circulation system in combination with a chamber wherein the air is conditioned for circulation in a building, a casing of enlarged cross sectional area supplied with returning air currents, a grille above said casing through which said currents pass, a conduit for gravity flow air connected to the bottom of said casing, and a suction conduit for forced air connected with its intake at the top 10 of said casing at a position removed from said grille, said suction conduit branching into two conduits, and each of said conduits connected to the intake of a blower having a single discharge conduit into said chamber.

15 2. A forced air injector for a hot air furnace comprising a conduit having a wall dividing said conduit into an upper and a lower conduit, said upper conduit for natural draft air and said lower conduit for air under superatmospheric pressure, said lower conduit at its discharge end having a width approximately ten times its depth, and having a cross sectional area substantially half the area of the upper conduit.

3. A forced air injector for a hot air furnace comprising a conduit having a wall dividing said conduit into an upper and a lower conduit, said upper conduit for natural draft air and said lower conduit for air under superatmospheric pressure, said lower conduit at its discharge end having a width approximately ten times its depth, and having a cross sectional area substantially half the area of the upper conduit, and a baffle extending beyond the discharge end of said dividing wall and inclined upwardly.

4. A forced air injector for a hot air furnace comprising a conduit having a wall dividing said conduit into an upper and a lower conduit, said upper conduit for natural draft air and said lower conduit for air under superatmospheric pressure, said lower conduit at its discharge end having a width approximately ten times its depth, and having a cross sectional area substantially half the area of the upper conduit, a baffle extending beyond the discharge end of said dividing wall and inclined upwardly, and means for inducing a steady non-eddying current of air through said lower conduit.

5. A combined gravity flow and forced air circulation system in combination with a chamber wherein the air is conditioned for circulation in a building, comprising in combination with a grille, a casing of enlarged cross sectional area through which air currents are drawn, a conduit of reduced cross sectional area extended from the bottom of said casing through which a gravity flow of air passes, a wide shallow conduit connected to said conduit of reduced cross section and through which a gravity flow of air passes into said chamber, a second wide shallow conduit below said first noted conduit through which forced air currents pass to said chamber, a suction conduit extending into the upper part of said casing at one end and connecting with said second shallow conduit at its other end, and air impelling means in said conduit.

RUDOLF JOVANOVITZ.
